UNITED STATES PATENT OFFICE

169,226

RULER

Harry Otis Sandberg, Boston, Mass.

Application December 9, 1947, Serial No. 143,071

Term of patent 14 years

(Cl. D52—1)

To all whom it may concern:

Be it known that I, Harry O. Sandberg, a citizen of the United States, residing at Boston, county of Suffolk, State of Massachusetts, have invented a new, original, and ornamental Design for a Ruler, of which the following is a specification, reference being had to the accompanying drawing, forming a part thereof.

Fig. 1 is a plan view of a ruler, showing my new design; Fig. 2 is an end elevation looking in the direction of the arrows 2—2 of Fig. 1; Fig. 3 is an underside plan looking in the direction of the arrows 3—3 of Fig. 2; and Fig. 4 is a cross-section of the ruler taken upon the line 4—4 of Fig. 3 looking in the direction of the arrows.

I claim:

The ornamental design for a ruler, substantially as shown.

HARRY OTIS SANDBERG.
